RADIO RECEIVING SYSTEM

Arthur A. Schoen, Woodhaven, and Arthur A. Blyth, Brooklyn, N. Y., assignors to Radio Corporation of America, a corporation of Delaware

Application November 13, 1929, Serial No. 406,756

13 Claims. (Cl. 250—20)

This invention relates to radio reception and has as its prime object the provision of a novel method and means for reducing image frequency response in a superheterodyne receiver.

5 It often occurs, when utilizing a superheterodyne receiver, that when the local oscillator thereof is tuned to obtain beat frequency energy with a desired station, another station is heard, which, of course, is undesirable. This interference is 10 due to the fact that the undesired station produces the same beat frequency with the local oscillator that the desired station does; and, in the past was avoided by manually tuning the oscillator to another frequency either above or below 15 its former frequency depending upon its former relationship with the desired station. However, to most radio receiver operators, such procedure is highly bothersome as it involves additional careful manipulation of the oscillator tuning 20 dials.

Accordingly, another object of this invention is to provide a superheterodyne receiver wherein the shift in oscillator frequency to reduce image frequency response is accomplished automatically.

25 In addition, we have found, depending upon the location in which the receiver is placed, that image frequency response is present only over a portion of the range of frequencies to which the receiver is responsive. Therefore, if the receiver is taken from one locality to another, the range or portion of the scale on which image frequency response occurs, changes both in magnitude and relative angular position; or in other words, in frequency band width and in position 30 on the frequency spectrum.

35 Hence, to provide an automatic change-over device for shifting oscillator frequency variable in width and position is a further object of this invention.

40 Briefly, according to a preferred embodiment of our invention, the foregoing objects are carried out by inserting a reactance in the tunable control circuit of the superheterodyne local oscillator by means of a switching arrangement au-

45 tomatically operable during the manipulation of the variable element of the tunable circuit which controls the frequency of the local oscillator. As the switching mechanism is in the form of a commutator mounted upon the element varying the 50 frequency of the local oscillator generator, the angular position at which change-over occurs can be readily controlled. By means of a variable contact, the portion or width of the frequency band in which frequency shift is accomplished,

55 is made variable.

The features of this invention which we believe characterize it are pointed out with particularity in the appended claims; however, our invention may best be understood both as to its mode of operation and construction by referring to the accompanying drawing which, of course, is given solely by way of illustration and not by way of limitation.

Referring to it,

Figure 1 is a diagrammatic illustration of a superheterodyne receiver embodying the principles of our invention;

Figure 2 illustrates a mechanism for providing variable frequency range change-over both in magnitude and position; and,

Figures 3 and 4 indicate alternative means for causing a predetermined frequency shift in an oscillation generator.

Turning to Figure 1, numeral 2 indicates an antenna which may be a loop or any other desired type of antenna feeding energy into an untuned amplifier, comprising preferably a screen grid vacuum tube 4, for the purpose of preventing radiation from subsequent apparatus in the receiver over antenna 2. The output of amplifier 4 is fed into an oscillating detector OD which in turn feeds beat frequency energy into a tuned intermediate frequency amplifier 6 tuned to a constant frequency. The output of the intermediate frequency amplifier 6 is fed into a detector or rectifier 8, rectified, and thence fed if desired, into a relatively low frequency amplifier 10 and thence translated by any suitable means such as a telephone 12. In order to control and vary the frequency of oscillation of the oscillating detector or local generator of oscillations a tunable circuit 14 is provided comprising an inductive reactance 16 and a capacitive reactance 18 the latter having a straight line frequency characteristic and having fixed stator plates 20 and grounded rotor plates 22.

In order to translate signals from a desired station, the rotor plates of the condenser in tunable circuit 14 are varied by means of knob 24 and shaft 26 until the local oscillation generator 100 produces energy of correct frequency to give a beat note frequency with the desired station corresponding to the tuning of intermediate frequency amplifier 6.

As already indicated, over a given range of frequencies image frequency response is present and objectionable. To obviate this we provide a commutator or switching mechanism X which, over a given range of frequencies, pulls the oscillator frequency from a frequency higher than the de-

sired station frequency to one below. Over that range of frequencies, by means of the commutator or switching mechanism X, a fixed reactance 28 is connected into circuit with the tunable circuit. Reactance 28 in the embodiment shown is a condenser of fixed value. As the switching arrangement is fixed to the control shaft 26 its action becomes, of course, automatic during the troublesome range where image phenomena 10 occur.

The switching arrangement is shown in greater detail in Figure 2 together with the means for making variable the magnitude and position of the range of frequencies at which change-over 15 occurs. More specifically, the switching or change-over mechanism comprises a disk of insulating material 30 having an insulating hub 32. By means of a set screw 34 the disk and hub can be placed at any desired angular position on shaft 26. In this manner the position 20 in the frequency spectrum at which frequency shift over occurs is readily varied.

Hub 32 carries a metallic commutator segment 36 and disk 30 carries a metallic segment 38. Both 25 segments are connected together by means of a metallic connecting piece 40 contacting with the under surface of segment 38 and thence over one surface of disk 30 to contact with the under surface of segment 36 at 42. Segment 36 is grounded by means of a contacting element 44.

One side of condenser 28 is connected to stator plates of condenser 20 and the other side is connected to ground through a contacting member 46 and segment 38 only when member 46 is 35 contacting with segment 38. Contacting element 46 is carried by means of screw clamps 48, 50 on an insulating support 52 and, accordingly, may be varied in position along segment 38 as shown by the dotted lines. This variation, of 40 course, gives the magnitude or range width at which it is desired that frequency change-over of the oscillator be made.

Another way of causing shift of oscillator frequency, from frequencies above desired stations 45 to that below the stations for reducing image frequency response, is shown in Figure 3 wherein to the rotor plates 22 of the oscillator condenser, areas 54 are added so that for a given range the desired shift in frequency takes place.

50 In the event that it is desired to shift the oscillator frequency in the reverse manner, apparatus as shown in Figure 4 may be resorted to wherein by means of the cut away portions 56, on the oscillator rotor condenser plates 22, the 55 change-over will be from a lower to a higher frequency.

Having thus described our invention what we claim is:—

1. In a superheterodyne receiver, an oscillation generator comprising a tube having a tunable input circuit for controlling the frequency thereof, said tunable circuit comprising a pair of unlike reactances at least one of which is continuously variable to alter the frequency of the tunable circuit, means for continuously altering the reactance of the variable reactance over a range, and means for adding a fixed like reactance to said alterable reactance over a predetermined fractional portion only of its range.
2. An oscillation generator comprising an electron discharge tube including a tunable input circuit for controlling the frequency thereof, said tunable circuit comprising a fixed inductance and a variable capacity having a straight line frequency characteristic and being continuously va-

riable to alter the frequency of the tunable circuit over a given range, and means for automatically connecting a fixed capacity to said variable capacity over a portion only of its range.

3. In a receiver, a signal amplifier circuit, a local oscillator stage including a tube provided with a tunable input circuit, an amplifier tuned to a predetermined beat frequency, said tunable input circuit including a pair of reactances of opposite sign, means for varying one of said reactances to produce said beat frequency with amplified different signals, and additional means mechanically operative with said varying means, and including a fixed reactance, for producing said beat frequency with a desired signal without image interference. 80

4. In a superheterodyne receiver, a signal amplifier circuit, including a screen grid tube, a local oscillator stage including a tube provided with a tunable input circuit, an amplifier tuned to a predetermined beat frequency, said tunable input circuit including a pair of reactances of opposite sign, means for varying one of said reactances to produce said beat frequency with amplified different signals, and additional means mechanically operative with said varying means, and including a fixed reactance of the same sign as the variable reactance, for producing said beat frequency with a desired signal without image interference. 95

5. In a receiver, a signal amplifier circuit, a local oscillator stage including a tube provided with a tunable input circuit, an amplifier tuned to a predetermined beat frequency, said tunable input circuit including a pair of reactances of opposite sign, means for varying one of said reactances to produce said beat frequency with amplified different signals, and additional means mechanically operative with said varying means, and including a fixed capacity, for producing said beat frequency with a desired signal without 100 image interference. 110

6. In a receiver, a signal amplifier circuit, a local oscillator stage including a tube provided with a tunable input circuit, an amplifier tuned to a predetermined beat frequency, said tunable input circuit including an inductance and a capacity, means for varying said capacity to produce said beat frequency with amplified different signals, and additional means mechanically operative with said varying means, and including a fixed reactance, for producing said beat frequency with a desired signal without 115 image interference. 125

7. In a receiver, a signal amplifier circuit, a local oscillator stage including a tube provided with a tunable input circuit, an amplifier tuned to a predetermined beat frequency, said tunable input circuit including an inductance and a capacity, means for varying said capacity to produce said beat frequency with amplified different signals, and additional means mechanically operative with said varying means, and including a fixed capacity for producing said beat frequency, with a desired signal without image interference. 130

8. In a superheterodyne receiver, a signal amplifier circuit, including a screen grid tube, a local oscillator stage including a tube provided with a tunable input circuit, an amplifier tuned to a predetermined beat frequency, said tunable input circuit including an inductance and a capacity, means for varying said capacity to produce said beat frequency with amplified different signals, and additional means mechanically and simultaneously operative with said varying means, and including a fixed condensive reactance, for pro- 140 145 150

- ducing said beat frequency with a desired signal without image interference.
9. In a superheterodyne receiver, a signal amplifier circuit, including a screen grid tube, a local oscillator stage including a tube provided with a tunable input circuit, an amplifier tuned to a predetermined beat frequency, said tunable input circuit including an inductance and a capacity, means for varying said capacity to produce said beat frequency with amplified different signals, and additional means mechanically and simultaneously operative with said varying means, and including a fixed capacity for producing said beat frequency with a desired signal without image interference. 80
10. In a superheterodyne receiver an untuned radio frequency amplifier including a screen grid tube, a local oscillator including an electron discharge tube provided with a tunable input circuit, an intermediate frequency amplifier, said oscillator input circuit including a fixed inductance and a capacity, means for varying said capacity to produce said intermediate frequency with amplified different signals, and additional means 85 mechanically and simultaneously operative with said capacity varying means, and including a fixed reactance, for connecting the latter to said capacity to produce said intermediate frequency with a desired signal without image interference. 90
11. In a superheterodyne receiver an untuned radio frequency amplifier including a screen grid tube, a local oscillator including an electron discharge tube provided with a tunable input circuit, an intermediate frequency amplifier, said oscillator input circuit including a fixed inductance and a variable capacity having a straight line frequency characteristic, means for varying said capacity to produce said intermediate frequency with amplified different signals, and additional 100 means operative with said capacity varying means, and including a fixed reactance, for connecting the latter to said capacity to produce said intermediate frequency with a desired signal without image interference. 105
12. In a superheterodyne receiver an untuned radio frequency amplifier including a screen grid tube, a local oscillator including an electron discharge tube provided with a tunable input circuit, an intermediate frequency amplifier, said oscillator input circuit including a fixed inductance and a variable capacity having a straight line frequency characteristic, means for varying said capacity to produce said intermediate frequency with amplified different signals, and additional 110 means operative with said capacity varying means, and including a fixed capacity, for connecting the latter to said capacity to produce said intermediate frequency with a desired signal without image interference. 115
13. A local oscillator, adapted for use in conjunction with a source of signals of a desired frequency range and a beat frequency utilization circuit, comprising a tube having a resonant input circuit adapted to be coupled to the source and an output circuit adapted to be coupled to said beat circuit, a variable tuning condenser in said input circuit having a grounded rotor element, a fixed condenser having one side thereof connected to the stator element of the tuning condenser, and grounded means, operative with said rotor element through a portion of said range, adapted to connect the other side of said fixed condenser to said rotor element. 120
14. A local oscillator, adapted for use in a superheterodyne receiver provided with a signal input circuit and an intermediate frequency amplifier, comprising a tube having a tunable input circuit including a variable condenser for adjusting the oscillator through a range of oscillation frequencies adapted to heterodyne with a desired range of signal frequencies separated from said oscillation frequencies by said intermediate frequency, and means, movable with the variable element of the condenser, for changing the effective capacity of said tunable input circuit through a portion of said oscillation frequency range to shift the oscillation frequency values in said portion to values capable of producing said intermediate frequency with the desired signals but not with undesired signal image frequencies. 125
15. A local oscillator, adapted for use in a superheterodyne receiver provided with a signal input circuit and an intermediate frequency amplifier, comprising a tube having a tunable input circuit including a variable condenser for adjusting the oscillator through a range of oscillation frequencies adapted to heterodyne with a desired range of signal frequencies separated from said oscillation frequencies by said intermediate frequency, and means, movable with the variable element of the condenser, for increasing the effective capacity of said tunable input circuit through a portion of said oscillation frequency range to shift the oscillation frequency values in said portion to values capable of producing said intermediate frequency with the desired signals but not with undesired signal image frequencies. 130
16. A local oscillator, adapted for use in a superheterodyne receiver provided with a signal input circuit and an intermediate frequency amplifier, comprising a tube having a tunable input circuit including a variable condenser for adjusting the oscillator through a range of oscillation frequencies adapted to heterodyne with a desired range of signal frequencies separated from said oscillation frequencies by said intermediate frequency, and means, movable with the variable element of the condenser, for decreasing the effective capacity of said tunable input circuit through a portion of said oscillation frequency range to shift the oscillation frequency values in said portion to values capable of producing said intermediate frequency with the desired signals but not with undesired signal image frequencies. 135
17. A local oscillator, adapted for use in a superheterodyne receiver provided with a signal input circuit and an intermediate frequency amplifier, comprising a tube having a tunable input circuit including a variable condenser for adjusting the oscillator through a range of oscillation frequencies adapted to heterodyne with a desired range of signal frequencies separated from said oscillation frequencies by said intermediate frequency, and means, movable with the variable element of the condenser, for changing the effective capacity of said tunable input circuit through a portion of said oscillation frequency range to shift the oscillation frequency values in said portion to values capable of producing said intermediate frequency with the desired signals but not with undesired signal image frequencies and additional means for varying the magnitude of said portion and the position thereof in said oscillation frequency range. 140
18. An oscillation generator comprising an electron discharge tube having a tunable input 145

circuit and an output circuit having a feedback coupling to said input circuit, said input circuit comprising a condenser having stator and rotor plates, a shaft on which said rotor plates are mounted and means for abruptly shifting the resonant frequency of said input circuit comprising a fixed condenser having at least two plates, a conductive connection between one of said plates and the stator plates of the tuning

condenser and means for connecting the other plate of said fixed condenser to the said rotor plates, said means comprising a metallic segment, an insulating disc on which said segment is mounted said disc being loosely mounted on said shaft and means for retaining said disc in any desired angular position on said shaft. 80
